UNITED STATES PATENT OFFICE.

RALPH E. BATES, OF PHILADELPHIA, PENNSYLVANIA, ASSIGNOR TO JOHN NAZEL,
OF PHILADELPHIA, PENNSYLVANIA.

FLUID-POWER HAMMER.

1,082,580.

Specification of Letters Patent.

Patented Dec. 30, 1913.

Application filed January 16, 1913. Serial No. 742,395.

To all whom it may concern:

Be it known that I, RALPH E. BATES, a citizen of the United States, residing in the city of Philadelphia, county of Philadelphia, and State of Pennsylvania, have invented certain Improvements in Fluid-Power Hammers, of which the following is a specification.

My invention is a fluid power hammer having a hollow ram movable in a cylinder on a stationary piston through which the interior of the ram is connected with a power cylinder and the atmosphere under control of peculiar valve mechanism.

It is a leading object of this invention to provide improved means for effecting the suspension, the continuous operation, the single stroke and the "vising" action of the ram, in a simple, efficient and durable construction of comparatively high power.

In the accompanying drawings, Figure 1 is a front elevation of a ram embodying my improvements; Fig. 2 is a side elevation thereof; Fig. 3 is a top view of the same; Fig. 4 is a sectional view taken on the line $y-y$ of Fig. 2; Fig. 5 is a sectional view taken on the line $z-z$ of Fig. 1; Fig. 6 is a vertical sectional view through the power cylinder with the power piston in the opposite position to that shown in Fig. 5; Fig. 7 is a bottom plan of the detached head of the hammer with a part broken away; Fig. 8 is a top plan of the detached head with the cap removed and a part broken away; Fig. 9 is a sectional view taken on the line $a-a$ of Fig. 8 and the lines $a'-a'$ of Figs. 5 and 10; Fig. 10 is a sectional view on the lines $b-b$ of Figs. 8 and 9; Fig. 11 is a sectional view on the lines $c-c$ of Fig. 8 and $c-a'$ of Fig. 10; Fig. 12 is a sectional view on the lines $d-d$ of Figs. 8 and 11; Fig. 13 is a sectional view taken transversely through the rotary valve showing the relation of the ports for holding the ram in the elevated position while the power piston is reciprocating, and Fig. 14 is a sectional view taken transversely through the rotary valve showing the relation of the ports for operating the ram under full pressure.

The hammer, in the form illustrated in the drawings, comprises the anvil 1 and the housing 2, through the base 3 whereof the anvil extends. The housing contains the

pitman chamber 4, the power cylinder 5 and the ram cylinder 6. A power piston 7 is reciprocated in the cylinder 5 by a pitman 8 disposed in the chamber 4. The pitman is operated through its connection with a crank 9 of a shaft 10 which is journaled in the bearings 11 and is provided with the respective loose and fixed pulleys 12 and 13. A ram piston 14 is fixed in the cylinder 6, the piston having a top 15 which engages and closes the top of the cylinder to which it is fixed by the bolts 16. A hollow ram 17 is provided with an outer cylindrical surface adapted for making full contact throughout its length therein with the surface of the cylinder 6 within which it reciprocates, the cylindrical interior surface of the ram working on the head 14' of the piston 14 which contains the through passage 18 adapted to be closed by the valve (a plug) 19 fixed on the bottom of the ram.

The bottom of the cylinder 6 has fixed thereto the downwardly extending guides 20 which engage the ram 17 and provide an extended lateral bearing and support therefor, particularly through the lower part of its movements and against tendencies to vibrate due to blows struck by the die 21 on work supported by the anvil block 22. These guides have the flat bearings 20' which engage like surfaces 17' of the ram to prevent the latter from turning.

The head 14' is provided with the passages 23 and 24 communicating with the chamber 25 containing the ball valve 26 which is adapted for closing the passage 24, the passages and chamber forming a by-pass 90 adapted for permitting a restricted flow of air between the interior of the ram and the passage 18 of the piston around the valve 19 when entered in the piston below the passage 24.

A head 27 is secured on the housing 2 over the cylinder 5 by the bolts 28, and to the head 15 by the bolts 29, the head having a cap 30 secured thereon by the bolts 31 and the cap containing the passage 32. The head 27 contains the cylindrical valve seat 33 which is connected by the passage 34 with the top of the cylinder 5, by the passage 35 with the passage 18, by the passage 36 with the chamber 37, by the passage 38 (through 105 the port 39 controlled by the valve 40) with

the atmosphere, by the passage 41 (through the port 42 controlled by the valve 43 and the passage 41') with the passage 35, by the passage 44 (through the port 45 controlled by the valve 46) with the passages 41' and 35, and by the passage 47 (through the port 48 controlled by the valve 49) with the atmosphere.

A cylindrical valve 50, disposed in the seat 33, is provided with the communicating ports 51, 52, 53 and 54; the port 51 being adapted for communicating with the ports 34 and 36, the ports 52 and 53 for communicating simultaneously with the passages 41 and 38 respectively or 44 and 47 respectively, and the port 54 adapted for communication with the passage 35.

The valve 50 is rocked through the connection of its stem 55 and a member 56, which coacts with a lever 57 having a handle 58 and a jaw 59, the lever being fulcrumed on a bearing 60. The lever is operated by hand and by the treadle mechanism comprising the parts 61, 62 and 63.

The power piston 7 is provided with a port 64 adapted for registration at the upper limit of its movement with a passage 65 in constant communication with the passage 34 and at the lower limit of its movement with a port 66 in constant communication with the port 67 through the chamber 68, the latter being in communication with the cylinder 5 through the port 67 when the ports 64 and 66 are in registration at the lower limit of movement of the piston.

In operation, when the valve 50 is in the position shown in Fig. 13, (closing the passages 35, 36, 38, and 41 and connecting the passage 34 with the passages 44 and 47 through the ports 52 and 53 now registering with the latter passages), the ram 17 will be held stationary in the elevated position while the piston 7 reciprocates. In this relation, upon the rise of the piston 7, air is forced through the passages 34, 51, 53, 47 and 48 to the atmosphere, the valve 49 being lifted to open the port or passage 48. When the piston 7 moves down, the partial vacuum induced in the cylinder 5 exhausts air through the passages 34, 51, 52, 44, 45, 41' and 18, from the interior of the ram, the valve 46 being forced downwardly to open the port or passage 45 and connect the passages 44 and 41'.

When the valve 50 is in the position shown in Fig. 14, connecting the passages 34 and 35 through the passages 51 and 54, the full power of the reciprocating piston 7 is exerted upon the ram 17 to effect its continuous reciprocation by the compression and exhaustion of air therein.

When the valve 50 is in the position shown in Figs. 10 and 12, the upward movement of the piston 7 forces air through the connected passages 34, 51, 52, 41, 42, 41',

35 and 18 to the interior of the ram 17, the valve 43 being lifted to open the port or passage 42. In the downward movement of the piston, the exhausting action holds the valve 43 down to close the port 42 and the passage 41', while the valve 40 opens the port 39 to admit air through the connected passages 38, 53 and 34, to the cylinder 5. Consequently the ram is held down in the "vising" position or caused to act with the anvil as a vise. In this position, the chamber 37 is in communication with the cylinder 5 and the interior of the ram 17 so that air is compressed therein and acts on the ram in the vising operation.

As the reciprocating ram 17 approaches the limit of its upward movement, the plug 19 closes the passage 18 and the air in the ram is trapped, excepting that escaping through the by-pass which is finally closed by the action of the ball 26 due to the pressure, the trapped air cushioning the ram and giving it an initial impulse downwardly.

When the reciprocating piston 7 reaches the position of registration between the passages 64 and 65 air in front of it can escape to the atmosphere to relieve the mechanism, the passage 34 being connected with the passage 65 in all positions of the piston. When the piston 7 reaches the position of registration between the ports 64 and 66 atmospheric air flows thereby to the chamber 68 and thence through the passage 67 to the cylinder 5 in front of the piston. It will be understood that the desired period of relief is thus obtained.

Having described my invention, I claim:

1. A power hammer comprising a cylinder containing a stationary piston having a passage therethrough, a hollow ram adapted to reciprocate in said cylinder on said piston, a second cylinder, a piston adapted to reciprocate in said second cylinder, passages connecting said second cylinder with said first named passage and with the atmosphere, and valve mechanism for controlling the flow of motive fluid through said passages.

2. A power hammer comprising a cylinder containing a fixed piston having a fluid passage, a hollow ram adapted to be reciprocated in said cylinder on said piston by fluid communicated to and withdrawn from its interior through said passage, and a valve within said ram for closing said passage and trapping motive fluid in said ram.

3. A power hammer provided with a cylinder containing a fixed piston having a motive fluid passage therethrough, means comprising a cylinder and piston for introducing motive fluid to and withdrawing it from said ram through said fixed piston to effect the reciprocation of said ram; and valve mechanism for trapping motive fluid be-

tween said fixed piston and ram whereby the reverse movement of the latter is cushioned and its forward movement induced.

4. A power hammer provided with a cylinder containing a fixed piston, a hollow ram adapted to reciprocate in said cylinder on said piston, a power cylinder, a power piston adapted to reciprocate in said power cylinder, passages adapted for connecting said power cylinder with the atmosphere and with the interior of said ram through said fixed piston, and valve mechanism for controlling said passages.

5. A power hammer comprising a ram cylinder containing a fixed piston, a hollow ram adapted to reciprocate in said cylinder on said piston, a power cylinder, a power piston adapted to reciprocate in said power cylinder, passages adapted for connecting said power cylinder with the atmosphere and with the interior of said ram through said fixed piston, a manually operated valve and automatically operated valves whereby, when said manually operated valve is in different positions, said ram is suspended, constantly reciprocated and held in the "vising" position by the action of said power piston.

6. A power hammer provided with a ram cylinder; a fixed piston therein, a hollow ram adapted to reciprocate in said cylinder on said piston; a power cylinder, a power piston adapted to reciprocate in said power cylinder; a cylindrical valve seat; passages connecting said seat with the atmosphere, the interior of said ram and said power cylinder, valve mechanism comprising automatically acting valves for controlling the flow of air between said seat and the atmosphere, and a rotary valve in said seat for controlling the flow of air therethrough between said passages.

7. A power hammer comprising a cylinder containing a stationary piston, a hollow ram adapted to reciprocate in said cylinder on said piston, a power cylinder, a power piston adapted to reciprocate in said power cylinder, a valve seat, a passage connecting said valve seat with the interior of said ram, an automatic valve for controlling said passage, a passage connecting said valve seat with said power cylinder, a passage adapted for connecting said seat with the atmosphere, an automatic valve for controlling said last named passage, and a valve movable relatively to said seat, whereby said ram is held suspended during the reciprocation of said power piston.

8. A power hammer comprising a cylinder containing a stationary piston, a hollow ram adapted to reciprocate in said cylinder on said piston, a power cylinder, a power piston adapted to reciprocate in said power cylinder, a passage connecting said power cylinder with the interior of said ram

through said stationary piston whereby said power piston is adapted for reciprocating said ram, and a valve for controlling said passage.

9. A power hammer comprising a cylinder containing a fixed piston, a hollow ram adapted to reciprocate in said cylinder on said piston, a power cylinder, a power piston adapted to reciprocate in said power cylinder, passages whereby said power cylinder is adapted to be connected with the interior of said ram through its piston and with the atmosphere, an automatic valve for permitting the flow of air from said power cylinder to the interior of said ram on the forward stroke of said power piston and for preventing the flow of air from the interior of said ram to said power cylinder on the reverse stroke of the power piston, and an automatic valve for permitting air to flow from the atmosphere to the power cylinder on the reverse stroke of the power piston and for preventing air from flowing from the power cylinder to the atmosphere on the forward stroke of the power piston.

10. A power hammer comprising a cylinder containing a fixed piston, a hollow ram adapted to reciprocate in said cylinder on said piston, a power cylinder, a power piston adapted to reciprocate in said power cylinder, passages connecting said power cylinder with the interior of said ram, passages connecting said first named passages with the atmosphere, and valve mechanism for controlling said passages.

11. A power hammer comprising a cylinder, a hollow ram adapted to be reciprocated in said cylinder, a piston fixed in said cylinder, a head on said piston engaging said ram, said piston and head having a passage therethrough communicating with the interior of said ram, and means for alternately communicating pressure and suction through said passage to the interior of said ram to effect its reciprocation.

12. A power hammer having a cylinder, a stationary piston therein, a hollow ram adapted to reciprocate in said cylinder on said piston, a power cylinder, a power piston adapted to reciprocate in said power cylinder, a chamber, a valve seat, a passage connecting said power cylinder and valve seat, a passage connecting said valve seat with the interior of said ram, a passage for connecting said valve seat with the atmosphere, a passage for connecting said valve seat with said chamber, and a valve movable relatively to said seat for controlling said passages.

13. A power hammer comprising a cylinder, a hollow piston having a head fixed to and closing an end of said cylinder, a hollow ram adapted to reciprocate in said cylinder on said piston, a power cylinder, a power piston adapted to reciprocate in said

power cylinder, a head fixed to and closing an end of said power cylinder, said heads being fixed together, and contiguous communicating passages in said heads whereby the interiors of said ram and power cylinders are connected.

14. A power hammer comprising a ram cylinder containing a ram, a power cylinder containing a piston, a passage connecting said cylinders, a valve for controlling said passage, shunt passages connecting said

first named passage with said ram cylinder in the rear of said ram, and a plurality of valves controlling said shunt passages.

In testimony whereof I have hereunto set my hand this 13th day of January, 1913, in the presence of the subscribing witnesses.

RALPH E. BATES.
